UNITED STATES PATENT OFFICE.

JOHN H. MORGAN AND CHARLES W. HUNTLEY, OF HOLYOKE, MASSACHUSETTS.

MEANS AND APPARATUS FOR EXTRACTING STATIC ELECTRICITY.

1,275,585.

Specification of Letters Patent. Patented Aug. 13, 1918.

Application filed February 25, 1915. Serial No. 10,463.

To all whom it may concern:

Be it known that we, JOHN H. MORGAN and CHARLES W. HUNTLEY, both citizens of the United States of America, and both 5 residents of Holyoke, in the county of Hampden and State of Massachusetts, have jointly invented new and useful Improvements in Means and Apparatus for Extracting Static Electricity, of which the following 10 is a specification, reference being had to the accompanying drawings and letters of reference marked thereon.

It is a well known fact that in the manufacture or finishing and treatment of paper 15 as well as in handling it, such as in ruling, calendering, printing, etc., the paper becomes charged with static electricity, causing the surfaces and sheets to adhere and to curl, thus rendering it difficult to handle 20 the paper conveniently, whether it be in sheets or otherwise.

The object of our invention is to provide a simple and effective means and mechanism by which static electricity may be easily 25 and satisfactorily removed from paper and other material, and we accomplish the object of our invention by the means, method and mechanisms hereinafter referred to.

For the purpose of illustrating our invention we show in the drawings one embodiment thereof as applied to a paper ruling machine.

In the drawings,

Figure 1 is a side elevation of the delivery 35 end of a ruling machine.

Fig. 2 is a front end elevation of the same.

Fig. 3 is a side elevation of the condenser.

Fig. 4 is a side view of a condenser plate.

Fig. 5 is an edge view of the same.

Fig. 6 is a side view of a separator member and Figs. 7 and 8 side and edge views 40 respectively of a spring brush.

In detail *a* indicates a condenser; *b*, plates therein; *c* separator; *d* an electric conductor leading to the condenser; *e* an electric conductor from the condenser to the ground; *f* brush stem supporting member; *g* brush stems; *h* brushes; *i* a sheet of paper; and *j* delivery box of ruling machine.

50 Describing now our invention as illustrated in the drawings and as one embodiment of our invention as applied to a paper ruling machine we arrange an electrical conductor *f* in suitable supports *k* at the delivery end of the ruling machine. The

rod *f* is preferably of copper and has pivotally mounted thereon the brush stems *g*, these being of suitable conducting material and being by preference mounted on the rod *f* by having their ends carried around the 60 rod with sufficient tightness so that they will at all times be in contact, yet sufficiently loose to permit of their being rotated thereon a trifle by the paper as it passes forwardly beneath the brushes *h*.

65 The brushes *h* are preferably arranged so that their edges almost contact with each other and so that they will be in contact with the surface of the paper in its passage.

A condenser comprising a series of thin 70 lead plates separated a short distance from each other and immersed in a liquid of low resistance in electrical connection with the static field and with the ground, serves to absorb all the objectionable static electricity in the paper or other material from which such electricity is being taken, the same being ultimately conducted from the condenser to the ground and dissipated.

We prefer the condenser plates be shaped 80 substantially as shown in Fig. 4, the upwardly projecting portions *l* and *m* being provided with over-hanging lips *n* and *o* for convenience in supporting the plate in the case. The plates are by preference about 85 one-sixteenth of an inch in thickness and we prefer to keep them separated from each other by the employment of a hard rubber separator similar to that illustrated in Fig. 6. We find a convenient method of supporting the separator plates to be by the employment of a hard rubber rod *p* resting on the upper edge of the central portion of the lead plates and with the separators 90 hanging on said rod *p*.

95 For a suitable fluid of low resistance we, as at present advised, prefer to employ dilute sulfuric acid, in the proportion of about four parts of water to one of acid, so as to give about 1,300 specific gravity.

100 Before the plates are mounted in the case we prefer that they first be carefully cleansed of all grease and foreign matter and for this purpose we find a bichlorate of potash bath effective. We also clean the 105 surfaces with sand-paper or a stiff brush. We prefer also to treat the negative plates with a bath or coating of litharge, this being prepared by mixing litharge with dilute sulfuric acid.

110

The plates with separators there-between are mounted in the case; the positive plates being electrically connected with each other and in electrical connection with the rod or conductor *f* and the negative plates being electrically connected with each other and with a grounded wire.

To give the best results the fluid in the case should substantially cover the portion 10 of the plates below the upright arms thereof.

The capacity of our condenser may be increased by increasing the number of plates. We find by practical tests that a condenser having eight positive and nine negative plates has sufficient capacity to absorb 15 and dissipate the static electricity ordinarily generated in eight ruling machines. When a single condenser is employed with more than one ruling machine, we prefer that the conductors from the rod *f* be in electrical connection with a common conductor and that the conductor *d* from the condenser extend to the central portion of this common rod or conductor and that the electrical conductors from the separate machines run to 20 the common conductor and be connected therewith at opposite sides of the point of connection of the conductor *d* with the common conductor.

30 It will readily be seen that our apparatus is adapted for extracting static electricity from all material, provided the gathering brushes be brought in contact therewith, or so close thereto as to in fact be within the 35 static electric field, so as to gather the static electric energy from the material enabling it to be transferred or absorbed through suitable conductors to the condenser, and from thence to the ground.

40 In the application of our invention to a printing press it simply becomes necessary to arrange the brushes so that they will be in electrical contact with the paper as it passes from point to point, it being preferable in all instances to have this contact 45 take place as the paper passes outwardly in sheets to the point where it is desired that it lay flat without curling or adhesion.

In the application of our invention to 50 calendering machines as the sheets of paper are delivered from the machine with great rapidity and force we find it very desirable that the brushes be spring pressed rather than to rely upon gravity as in the case illustrated in the application to a ruling machine. As an example of a simple spring 55 pressed brush we illustrate in the drawings in Figs. 7 and 8 a brush supporting stem formed of spring material, the supporting 60 end being of course firmly supported by clamps or other suitable means in such position that the brushes *h* will at all times be held in contact with the moving paper.

While the element or member herein referred 65 to as a "condenser" may also be termed

an accumulator element or a battery, none of which terms accurately describe or define such element or member and as any of these terms may be misleading and as this member operates in fact to absorb or draw 70 from the material the static electricity and is therefore an important element or member essential to the carrying out of the invention, applicants prefer to refer to the same as an "absorbing member" so that it 75 is immaterial whether such member falls within the technical or scientific definition of the term "condenser", "battery", "accumulator" or other technical term, as applicants have discovered that a member comprising 80 plates immersed in a fluid of low resistance electrically connected as herein pointed out results in a means, method or apparatus which causes the objectionable presence of static electricity to be removed from material 85 so charged.

It will readily be seen that very many modifications in detail of arrangement may be employed without departing from the spirit of our invention and we do not limit 90 ourselves to any specific detail herein described or referred to.

Having therefore described our invention what we claim as new and desire to secure by Letters Patent is:—

1. An apparatus for removing static electricity comprising a collector positioned in the static field, an absorbing member consisting of positive and negative plates immersed in a fluid of low resistance and suitable conductors from the collector to the absorbing element and from the latter to the ground.

2. The method of extracting negative static electricity comprising suitable gathering means in the static field, a conductor therefrom to the positive side of an absorbing member, a suitable conductor from the negative side of the absorbing member to the ground, positive and negative plates and a fluid of low resistance between the plates.

3. An apparatus for removing the objectionable presence of static electricity in material, comprising suitable collectors arranged in the static field, an absorbing member comprising a suitable case having positive and negative plates therein; suitable separating plates there between, a fluid of low resistance in contact with the plates and suitable grounding means substantially as shown.

4. In an apparatus for removing static electricity an absorbing member comprising a suitable case, lead plates therein suitably separated, a fluid of low resistance (consisting of dilute sulfuric acid of about 1300 specific gravity) between the plates, in combination with collecting means positioned in the static field, a suitable conductor between 120 125 130

the collector and the absorbing member and between the latter and the ground.

5. An apparatus for removing static electricity comprising a collector positioned in the static field, an absorbing member consisting of a series of lead plates immersed in a sulfuric acid solution and suitable conductors from the collector to the absorbing

element and from the absorbing element to the ground.
